UNITED STATES PATENT OFFICE.

OLIVER P. MOORE, OF SPOKANE, WASHINGTON.

OIL OR GAS BURNING SMELTING-FURNACE.

1,225,470.

Specification of Letters Patent.

Patented May 8, 1917.

Application filed August 2, 1916. Serial No. 112,759.

To all whom it may concern:

Be it known that I, OLIVER P. MOORE, a citizen of the United States, residing at Spokane, in the county of Spokane, State 5 of Washington, have invented a new and useful Oil or Gas Burning Smelting-Furnace; and I do hereby declare the following to be a full, clear, and exact description of the invention, such as will enable 10 others skilled in the art to which it appertains to make and use the same.

This invention relates to an oil or gas burning smelting furnace, and an object of 15 the invention is to improve, simplify, and render more practical and efficient the structure of smelting furnace illustrated, set forth and claimed in the patent to O. P. Moore, dated September 14, 1915, Patent Number 1,153,561.

20 Another object of the invention is to provide a device of this kind having means whereby all the gases of combustion may pass from the smelting chamber or crucible into the pre-heating and reduction chamber, and also having means whereby a larger exposure of the surface of ore in the smelting chamber is exposed to the heat, which pass through the interstices between the ore in the smelting chamber and the ore in the pre-heating and reduction chamber.

25 Another object of the invention is to provide means in the pre-heating and reduction chamber for retarding the ore in said chamber. In other words, to divide the ore and cause it to descend quickly, said means temporarily retaining, or retarding the ore, thereby obviating the employment of water cooled grates in the direct passage of the hot gases.

40 Another object of the invention is to provide means consisting of water cooled bars adapted to reciprocate through a water cooled plate which is set or embedded in the wall of the furnace back of the retaining or retarding means, thereby constituting means to push or inject the ore forwardly into the throat of the smelting chamber.

45 A further object of the invention is to provide means to permit all the air used in the combustion of the fuel in the smelting or refining chamber to be drawn through the walls between the flues, leading from the sides of the refining or smelting chamber from points just below the entrance of the jets of heat and connecting with the discharge flue beneath the floor of said chamber.

ber. The drawing of all the air used in the combustion of the fuel through passages in the walls between said flues, constitute means for cooling the support of the bottom of the smelting chamber and pre-heating the air before it enters the smelting or refining chamber, and at the same time permit the heat to be drawn directly from the smelting or refining chamber into the passages (which communicate with the discharge flue) for the purpose of further pre-heating the air.

50 A further object of the invention is to permit the ore and fluxes to be charged into the pre-heating and reduction chamber.

In practical fields, the details of construction may necessitate alterations, falling within the scope of what is claimed.

The invention comprises further features 75 and combination of parts, as hereinafter set forth, shown in the drawings, and claimed.

In the drawings:—

Figure 1 is a vertical sectional view through the improved furnace constructed 80 in accordance with the invention.

Fig. 2 is a sectional view on line 2—2 of Fig. 1 looking in the direction of the arrow.

Fig. 3 is a transverse sectional view on line 3—3 of Fig. 1.

Fig. 4 is a transverse sectional view on line 4—4 of Fig. 1.

Fig. 5 is a fragmentary sectional perspective view of the base of the furnace, clearly showing the smelting chamber, showing the flues 15 and 16 in full and also the flue 23^b in full, and the flues 23 and 23^a in dotted lines.

Fig. 6 is a detail fragmentary perspective sectional view of the base of the furnace, 95 showing the smelting chamber, and illustrating the flues 23, 23^a and 23^b in full, and the flues 15 and 16 in dotted lines.

Referring more especially to the drawings, 1 designates a foundation, which may be constructed of concrete or cement or the like, in which an outlet flue 2 is constructed, and which flue may be connected to the chimney stack (not shown), in any suitable manner (not shown). The wall of this flue 100 is constructed of any suitable fire brick, as illustrated. Constructed upon and rising upwardly therefrom is the base wall 3 of the smelting furnace, and which base may be of any suitable shape or contour, and is 105 surrounded by a metallic sheeting 4, and at points directly opposite each other, the wall

of the base 3 is provided with openings 5, through which the heat injecting tubes 6 extend, for projecting the heat flames from any suitable fuel, such as oil, gas or powdered coal, upon the bath. The base 3 is provided with a smelting or refining chamber 7. The bottom 8 of the smelting chamber is provided with the usual form of cavity or depression 9, which is provided with a suitable furnace lining 10, which is constructed of any suitable material, for instance, fire clay or the like, and which lining overlies a portion of the upper edge of the bottom of the smelting or refining chamber, as shown at 11. Referring to Fig. 2 it is to be seen that one of the side walls of the base 3 is provided with an outlet passage or tap 12, for drawing off the slag from the top of the molten metal or bath in the chamber 7. Below the tap or opening 12 is a second opening or tap 13, for drawing off the molten metal. These taps or openings may be plugged in the usual manner (not shown) by means of clay plugs, which may be removed in any suitable manner when desired, for drawing off the slag and molten metal. The wall having the taps or openings 12 and 13 is provided with an opening 14 and door therefor, which is above the upper surface of the bath of ore, and by opening the door (not shown) from said opening, a suitable tool or implement may be inserted through the opening, for agitating slag upon the upper surface of the bath 35 of ore, so as to work the slag toward the tap or opening 12, whereby the slag may be easily drawn off. Leading from opposite sides of the smelting or refining chamber at points immediately below where the heat 40 flames enter said chamber are flues 15 having portions 16 extending under the bottom of the refining or smelting chamber, which flues are in communication with the flue 2 by means of the port 17. The furnace stack 45 rises upwardly from the base 3 of the furnace and is provided with a surrounding metallic sheeting 20. The upper end of the stack 19 is provided with an opening 21 concentric with the center of the stack, that is 50 in plan view, and through which opening, the ore and flux may be charged into the preheating and reduction chamber by any suitable device (not shown). This opening 55 21, may be closed by any suitable means (not shown). As shown clearly in Fig. 2, the walls 22 between the flues 15 and 16 are provided with air passages 23, which lead from opposite sides of the smelting or refining chamber, at points immediately below where the heat flames enter the smelting or refining chamber. These air passages have flue parts 23^a extending under the bottom of the smelting or refining chamber, but do not communicate with the discharge chamber and discharge flue 2^a and 2,

respectively. However, the air passages 23 and 23^a, as shown clearly in Fig. 2, communicate with the air passage 25. The upper part of the smelting or refining chamber has a passage or opening 26 of communication with the pre-heating and reduction chamber, so that the ore from the pre-heating and reduction chamber may pass into the refining chamber. Where the stack 19 rises from the base 3, tubular water 75 cooled bars 27 are embedded, which water cooled bars are supported upon the I-beams 28, which water cooled beams 27 act to reinforce the structure, and keep the same cool. Also embedded in the stack adjacent where 80 it rises from the base 3 are water cooled beams 29, through which rods 30 may be reciprocated in any suitable manner (not shown). Extending transversely of the 85 stack is a triangular beam 31, and about this metal beam, a substantially triangular or wedge shaped fire brick structure or arch 32 is constructed, the apex of which is finished off with a solid metallic beam 33 triangular in cross section, acting to protect 90 the fire brick structure, and together with the sides 34 (which are inclined) act to deflect the ore upon the ledge 35 at the lower part of the pre-heating and reduction chamber, where the ore, by means of the rods 30, 95 can be fed or projected through the opening 26 into the refining or smelting chamber. When smelting or refining ore, the pre-heating and reduction chamber receives the ore through the opening 21, including a 100 proper amount of lime and carbon. It is to be noted that the fire brick wedge shaped arch or structure 32 extends transversely of the pre-heating and reduction chamber, adjacent its lower portion. Said 105 arch or wedge shaped structure is wide enough to overlie or overhang the ledges 35 at the bottom of the pre-heating and reduction chamber, so that as the ore deposits into the pre-heating and reduction chamber 110 through the filling opening 21, the ore will be deflected by the inclined sides 34 of the wedge shaped arch toward and upon said ledges. The hot gases from the smelting or refining chamber are drawn into and 115 through the pre-heating and reduction chamber, by means of natural or mechanical draft, (owing to the opening 18^a being connected to and in communication with the chimney stack, not shown, but as described 120 in said Patent Number 1,153,561), thereby pre-heating and deoxidizing the ore prior to entering the smelting or refining chamber. The ore is held in the preheating and reduction chamber and out of the opening 125 26, between the pre-heating and refining chambers, by means of the ledges 35, which support the ore. By reciprocating the rods 30 (which are water cooled owing to the passing through the bars 29, through which 130

cold water circulates) the ore may be fed in any desired quantities, from the ledges 35 through the opening 26 into the smelting or refining chamber, and upon which ore or bath the heat flames from opposite sides of the smelting or refining chamber are projected. Through ebullition or boiling in smelting, the ore is distributed over the whole surface of the smelting zone, thereby exposing the greatest possible surface of the ore to the action of the heat. By inserting some suitable tool through the opening 14, the slag on the surface of the ore or bath may be agitated toward the outlet 12, through which the slag may be drawn, when the clay plug is removed, while the molten metal may be drawn off through the outlet 13, when its clay plug is removed.

The flue 2 is designed to be connected to the chimney stack, not shown, in the same manner as a similar flue in said O. P. Moore's Patent 1,153,561 would be connected. Furthermore, the opening 18^a is designed to be also connected to said chimney stack, as stated in said prior patent. However, these connections of communication with said chimney stack may have conventional means, not shown, whereby the draft may be controlled. Hence, when the connection 30 of communication between the opening 18^a is closed by any suitable or conventional means, not shown, and the connection of communication between the flue 2 and said chimney stack is open, a natural draft is created, in a manner hereinafter set forth, for instance, cold air is drawn through the air passage 25 and into one of the flues 23^a, which extends under the bottom of the smelting or refining chamber, and is in communication with the other flues 23^a (which extend under the bottom of the smelting or refining chamber) by means of the right angled extending flue part 23^b. The cold air circulates through the flues 23^a, 23^b and upwardly through said flues 23, which are substantially parts of the flues 23^a, and into the smelting or refining chamber. Therefore, a draft being created through the flues 15 and 16 and through the discharge chamber 2^a and the flue 2, the cold air will naturally pass off therethrough. The cold air in passing through said flues 23^a and 23 acts to cool the bottom of the smelting chamber, and this air, while cooling the bottom of the smelting chamber, in itself, becomes pre-heated before it enters the smelting chamber by the heat which is drawn from the smelting chamber through the flues 15 and 16, and out through the discharge chamber 2^a and the flue 2. This circuit is maintained, while smelting and refining the ore. However, while the ore and slag are being drawn from the smelting chamber, other ore is being pre-heated, while 60 on the ledges 35 of the preheating chamber, owing to drawing the heat from the smelting chamber into the preheating and reduction chamber, by causing an upward draft, which is created, by cutting off communication between the flue 2 and the chimney stack, and opening communication between the opening 18^a and the chimney stack. Hence, it will be seen that the relation between the flues 23, 23^a, and the air passage 25, is such as to provide an upward draft 75 into the preheating or reduction chamber 18, which is formed in the chimney stack 19. By causing this upward draft, the ore is preheated and deoxidized before entering the refining chamber, and after being so 80 preheated and deoxidized, the rods 30 are reciprocated, thereby discharging the ore through the opening 26 in the smelting or refining chamber.

The invention having been set forth, what 85 is claimed as new and useful is:—

1. In a furnace; the combination of a smelting or refining chamber and a pre-heating and reduction chamber in communication at its bottom with said refining chamber, and having a filling opening at its top axially with said opening of communication; of a wedge shaped arch extending transversely of said pre-heating chamber, adjacent the bottom portion thereof, just 90 above the opening of communication in substantially direct line with said filling, thereby dividing the ore and deflecting same upon opposite sides of the bottom of the pre-heating chamber, said opposite sides of the 95 bottom constituting ledges for retaining or retarding the ore in said pre-heating chamber; and means in opposite walls of the pre-heating chamber, adapted to be reciprocated at intervals, for feeding the ore through 100 said opening of communication, into said refining chamber.
2. In a furnace; the combination of a pre-heating and reduction chamber and a smelting or refining chamber in communication 105 at its top with said pre-heating chamber; of means, at opposite sides of the refining chamber adjacent the top, to throw flames over the surface of the bath; the lower portion of the base of the furnace having an 110 air passage, and air flues leading from the opposite sides of the refining chamber from points just below said means and connecting with said air passage beneath the floor of the refining chamber; a discharge chamber 115 and flue in the base of the furnace; and heat flues leading from the opposite sides of the refining chamber at points just below said means and extending under the floor of the refining chamber and communicating with the discharge chamber, the relation of said 120 heat flues and the air flues, and the air passage, and the discharge chamber being such as to provide a draft out through the discharge, a circuit of air passing from the air 125 130

flues through the heat flues, the relation between the air flues and the air passage being such as to provide a partial upward draft in the preheating chamber at a time when 5 the discharge may be closed.

In testimony whereof I have signed my

name to this specification in the presence of two subscribing witnesses.

OLIVER P. MOORE.
